UNITED STATES PATENT OFFICE.

EDWIN F. HULBERT, OF MILWAUKEE, WISCONSIN, ASSIGNOR TO NATIONAL PAPER CAN COMPANY, OF SOUTH NORWALK, CONNECTICUT, A CORPORATION OF DELAWARE.

METHOD OF SECURING VESSEL-CLOSURES.

1,319,083.

Specification of Letters Patent.

Patented Oct. 21, 1919.

Application filed April 25, 1914, Serial No. 834,362. Renewed April 11, 1919. Serial No. 289,463.

To all whom it may concern:

Be it known that I, EDWIN F. HULBERT, a citizen of the United States, residing at Milwaukee, in the county of Milwaukee and 5 State of Wisconsin, have invented a new and useful Method of Securing Vessel-Closures, of which the following is a full, clear, and exact description, reference being had to the accompanying drawings, forming part of 10 this specification, in which—

Figure 1 is a partial section showing the flanged closure in place, and Figs. 2, 3, 4 and 5 are similar views showing the successive operations performed in securing the 15 closure in place.

My invention relates to the securing of end closures in cans or similar packages, whether made of paper, metal, or other material.

20 The object of the invention is to provide a simple and effective method which will give a strong closure, resistant against jars or shocks in shipping, handling, etc. The invention is particularly applicable to the 25 securing of flanged closures in paper cans, although it may be applied to other receptacles and other materials. The main object of my invention is to lock the closure in place without the necessity of an interior 30 mandrel on which the receptacle body is supported. Heretofore such closures could be locked in place only at one end, owing to the necessity of an interior mandrel support; whereas my method provides for locking or 35 seaming the closure at one or both ends, on account of doing away with the necessity for an interior supporting mandrel.

In Fig. 1, 2 represents the side wall of the can or receptacle and 3 the closure having a circumferential outwardly projecting flange 4. In the first operation of the device 40 an exterior circular die 5 is used having a circumferential interior recess as shown at 6 and which die is preferably made in sections. An expandible interior die, part of which is shown at 7, is used in connection with the outer die and in the first operation the parts of the inner die 7 are forced out to cause the lips on the inner die to crimp 45 the walls of the closure flange and the can body outwardly into the groove in the outer die or anvil, all as shown in Fig. 2. In the 50 next movement, as shown in Fig. 3, the end die 8 having a depending edge portion and

a groove inside thereof is moved downwardly 55 within the outer die 2 and curves the registering edges of the closure flange and receptacle end inwardly and downwardly as shown. The pressure in this step, while sufficient to start the roll-over, is not sufficient 60 to overcome the support given to the cap by the pinching action of the inner and outer dies 5 and 7.

In the next step, shown in Fig. 4, a new outer die or anvil 9, which may be made in 65 sections, and a new expanding inner die 10 are used, but the pinching action between these dies remains the same as in the first movement, and the endwise moving die 11 acts downwardly, rolling-over the registering portions of the flange and receptacle and 70 into the seam form as shown.

In the fourth and final step, shown in Fig. 5, the inner and outer dies 12 and 13 are again changed and the order of movement is 75 reversed. That is, the endwise moving die 14 moves downward until it rests on the recessed portion of the anvil 12 carrying with it the rolled-over seam portion until this rolled-over seam portion is brought in contact 80 with the bottom 3 of the cap. The parts of the expanding inner die 13 are then forced outwardly and radially, as indicated by the arrow. The upper part of the recessed edge portion first comes in contact 85 with the upper part of the seam and the angle of contact forces the roll downwardly and outwardly into the recess or bead portion formed in the first movement. The pressure exerted by this inner die is sufficient to tightly compress the folds together, 90 lock the parts in place by forcing them into the bead or recess in the wall of the receptacle and give a hard wearing edge.

The advantages of my invention result 95 mainly from doing away with the need for interior mandrel support and providing for securing closures to both ends of the receptacle, if desired. This is accomplished by the pinching action of the inner and outer 100 dies, which gives sufficient support for the action of the endwise moving die. The locking of the seam in the bead gives a strong, secure joint, and the package is adapted to withstand blows and shocks. 105 Changes may be made in the material used, the shape and size of the receptacle and closure, etc., and the steps of the operation

may be changed somewhat from those as shown, without departing from my invention.

I claim:

- 5 1. The method of closing a can, consisting in placing a flanged cap within the open end of the can body, pinching together and beading the base of the flange together with the registering portion of the can body and thereby supporting the can against endwise movement, and rolling over the edges of the flange and body by endwise pressure while the can is thus supported, substantially as described.
- 10 2. The method of closing a can, consisting in placing a flanged cap within the open end of the can body, pinching together and beading a portion of the flange together with the registering portion of the can body and thereby supporting the can against endwise movement, and rolling over the edges of the flange and body by endwise pressure while the can is thus supported, substantially as described.
- 15 3. The method of closing a can consisting in placing a flanged cap within the open end of the can body, pinching together a portion of the flange together with the registering portion of the can body and thereby supporting the can against endwise movement, and rolling over the edges of the flange and body by endwise pressure while the can is thus supported, substantially as described.
- 20 4. The method of closing a can, consisting in placing a flanged dished cap within the open end of the can body, pinching and beading a portion of the flange together with the registering portion of the can body between an outer die surrounding the can body and an inner die inserted in the dished end of the cap, and thereby supporting the can against endwise movement, and rolling over the edges of the flange and body by endwise pressure while the can is thus supported, substantially as described.
- 25 5. The method of closing a paper can in which the can is engaged upon the exterior

only, consisting in placing a dished flanged paper cap within a paper can body, pinching together the base of the flange together with the registering portion of the can body between relatively movable inner and outer dies extending into the dished end of the cap and surrounding the can body respectively, rolling over the edges of the flange and body by the application of endwise pressure to form a rolled closure seam, and supporting the can against such endwise pressure by means of the pinching action of the dies, substantially as described.

6. The method of closing a paper can in which the can is engaged upon the exterior only, consisting in placing a dished flanged paper cap within the open end of a paper can body, pinching together and beading the base of the flange together with the registering portion of the can body by the action of relatively movable dies inserted within the dished end of the cap and surrounding the can body respectively, rolling over the edges of the flange and body by the application of endwise pressure thereby forming a rolled closure seam, and supporting the can against such endwise pressure by means of the pinching action of the dies on the beaded portion of the can, substantially as described.

7. The method of closing a can consisting in placing a flanged cap within a can body, pinching together a portion of the flange with the registering portion of the can body thereby forming an inwardly opening groove in the flange and supporting the can against endwise movement, rolling over the edges of the flange and can body by endwise pressure while the can is thus supported, and thereafter forcing a part of such rolled-over edges into the groove, substantially as described.

In testimony whereof, I have hereunto set my hand.

EDWIN F. HULBERT.
